2,525,113

SELF-ADJUSTING SACK HOLDER AND
FILLING VALVELouis B. Berg, Chicago, Ill., assignor, by mesne
assignments, to Robert Wilson Carter, Luling,
Tex.

Application November 15, 1947, Serial No. 786,209

5 Claims. (Cl. 226—58)

1

This invention relates to a device for holding sacks such as are ordinarily used as containers for grains, nuts, or other materials while the sacks are being filled from storage bins or chutes, and an object of my invention is the provision of a sack holder which will fully extend the opening of the sack over the discharge opening of the bin or chute in accordance with the size of the sack while the sack is being filled.

Another object of the invention is the provision of a valve in combination with the sack holding elements which will open the discharge opening of the bin or chute when the top of the sack is distended below said discharge opening by the sack holding elements and close said discharge opening when the sack holding elements are released from the sack after it is filled.

A particular advantage of the present invention resides in the fact that the sack is quickly attached to the sack holding elements and upon moving the sack holding elements to distend the top of the sack below the discharge opening of the bin or chute, the valve is simultaneously opened to fill the sack. When the sack is being released from the sack holding elements after it is filled the valve is automatically closed until the next sack is in distended position below the discharge opening. This results in a substantial reduction of time required for filling of the sacks and obviates spillage and waste of material since the sacks are always in filling position when the valve is opened.

Other advantages will be apparent to those versed in the art during the course of the following description.

These objects are accomplished as described in the following specification and illustrated in the accompanying drawings in which like characters of reference are employed to designate like parts throughout the various views of the drawings.

In the drawings:

Fig. 1 is a vertical cross-sectional view of the improved structure of the present invention and illustrating the relative positions of parts thereof just after a sack has been placed on the sack holding elements and prior to distension of the sack and opening of the valve for filling the sack.

Fig. 2 is a horizontal sectional view, partly in elevation, taken on the line 2—2 of Fig. 1.

Fig. 3 is a vertical cross-sectional view similar to Fig. 1 illustrating the relative positions of the parts of the structure when the sack is distended and the valve is opened for filling the sack.

Fig. 4 is a vertical cross-sectional view taken on the line 4—4 of Fig. 1.

2

Fig. 5 is an enlarged fragmentary cross-sectional view taken on the line 5—5 of Fig. 1.

With reference to the drawings it will be noted that the lower end of a bin, or chute 10 having an opening in its bottom, is provided with tubular members 11 attached to its exterior walls by welding, or other suitable means, at opposed points adjacent its discharge opening. These tubular members are located on opposite sides 5 of the opening in the bottom of the bin, or chute, and their axes are parallel with relation to each other and the plane of the discharge opening of the bin or chute for the reception of the legs of a U-shaped valve frame 12. Since the portion 10 15 of the frame 12 connecting the legs of the U-frame constitutes the handle for manual manipulation of the valve and the sack holding elements this end of the structure will hereinafter be called the front end.

20 Hooks 13 depend from each of the tubular members 11 immediately to the rear of the opening of the bin 10, these hooks forming the stationary sack holding elements of the structure. A valve plate 14 provided with suitably upwardly 25 extending side flanges 15 and a front flange 16 constitutes the valve means for opening and closing the discharge opening of the bin 10, the flanges 15 being attached to the outer sides of the U-frame 12, by welding or other suitable means, to 30 form supports for the full length of the valve plate 14 while the flange 16 constitutes a stop for limiting the rearward movement of the frame 12. Immediately forward of the flange 16 and depending from the legs of the U-frame 12 are hooks 17 comprising the movable sack holding elements of the structure. Longitudinal slots 18 formed by cutting away the outer walls of the tubular members 11 extend rearwardly from the front ends of the members 11 a sufficient distance to clear the 35 flanges 15 when the valve plate 14 is in its closed position.

It will be noticed that the points of the sack holding hooks 13 project rearwardly while the points of the hooks 17 project forwardly. Thus, when placing the sack in position for filling, as 45 in Fig. 1, the rear portion of the sack is stretched between the stationary hooks 13 after which the front portion of the sack is stretched between the movable hooks 17 which are attached to the frame 12. During the time the sack is being placed in position the valve plate 14 will, of course, be in the position indicated in Fig. 1 obstructing the discharge opening of the bin 10, and, therefore, no material will issue from the 50 bin during this operation. After the sack has 55

been secured in position on the hooks 13 and 17 the frame 12 carrying the hooks 17 and the valve plate 14 is pulled forward manually until the sack is stretched between the hooks 13 and 17 during which time the valve plate 14 has moved forwardly thereby opening the discharge opening from the bin 10. Thus, filling of the sack is started simultaneously with stretching of the sack to the filling position. All of these functions are accomplished with three simple manual movements. Stretching the sack over the hooks 13, stretching the sack over the hooks 17 and pulling the frame 12 forwardly.

When the sack has filled to the desired level, the frame 12 carrying with it the valve plate 14 which closes the discharge opening of the bin 10 is moved rearwardly and during the time the frame 12 is being moved rearwardly the sack is detached from one or the other set of the hooks 13 or 17 depending upon the level to which the sack has been filled. After the valve plate 14 has closed the discharge opening of the bin 10 any portions of the sack remaining attached to any of the sack holding hooks are disengaged and the sack is removed whereupon the foregoing sack filling cycle is repeated.

It should be noted that there is no limit to the forward movement of the frame 12, therefore, the top of the sack will be stretched to its fully opened position when the frame 12 is pulled forwardly thus eliminating any wrinkles in the sides of the sack while it is being filled. The minimum size of sack which can be held and filled with this device will be governed, of course, by the size of the opening of the bin or chute 10.

I claim:

1. In combination with a receptacle having a discharge opening through which material contained in said receptacle is discharged therefrom, a structure for controlling passage of material through said discharge opening and for distending and holding a sack beneath said discharge opening, said structure including a movable operating member having spaced leg portions, guiding elements fixedly supported by said receptacle and arranged to guide said spaced leg portions of said movable operating member for movement during actuation of said movable operating member, a valve member fixed to and movable with said movable operating member into and out of position where it closes said discharge opening, stationary sack holding elements in the form of hooks fixed to said guiding elements, and sack holding elements in the form of hooks fixedly mounted on and movable with said movable operating member and with respect to said stationary sack holding elements.

2. In combination with a receptacle having a discharge opening through which material contained in said receptacle is discharged therefrom, a structure for controlling passage of material through said discharge opening and for distending and holding a sack beneath said discharge opening, said structure including a U-shaped movable operating member having spaced leg portions, guiding elements fixedly supported by said receptacle and arranged to guide said spaced leg portions of said movable operating member for movement during actuation of said movable operating member, a valve member fixed to and movable with said movable operating member into and out of position where it closes said discharge opening, stationary sack holding elements in the form of hooks fixed to said guiding elements, and sack holding elements in

the form of hooks fixedly mounted on and movable with said movable operating member and with respect to said stationary sack holding elements.

5. In combination with a receptacle having a discharge opening through which material contained in said receptacle is discharged therefrom, a structure for controlling passage of material through said discharge opening and for distending and holding a sack beneath said discharge opening, said structure including a U-shaped movable operating member having spaced leg portions, tubular guiding elements fixedly supported by said receptacle and arranged to guide said spaced leg portions of said movable operating member for movement during actuation of said movable operating member, a valve member fixed to and movable with said movable operating member into and out of position where it closes said discharge opening, stationary sack holding elements in the form of hooks fixed to said guiding elements, and sack holding elements in the form of hooks fixedly mounted on and movable with said movable operating member and with respect to said stationary sack holding elements.

30 6. In combination with a receptacle having a discharge opening through which material contained in said receptacle is discharged therefrom, a structure for controlling passage of material through said discharge opening and for distending and holding a sack beneath said discharge opening, said structure including a U-shaped movable operating member having spaced leg portions, tubular guiding elements fixedly supported by said receptacle and arranged to guide said spaced leg portions of said movable operating member for movement during actuation of said movable operating member, a valve member fixed to and movable with said movable operating member into and out of position where it closes said discharge opening, stationary sack holding elements fixed to said guiding elements, sack holding elements fixedly mounted on and movable with said movable operating member and with respect to said stationary sack holding elements, said stationary and movable sack holding elements being in the form of pointed hooks with the points of the stationary sack holding elements being extended in a direction different from the direction of extension of the points of the movable sack holding elements, and means for limiting movement of said movable operating member in one direction.

45 7. In combination with a receptacle having a discharge opening through which material contained in said receptacle is discharged therefrom, a structure for controlling passage of material through said discharge opening and for distending and holding a sack beneath said discharge opening, said structure including a U-shaped movable operating member having spaced leg portions, tubular guiding elements fixedly supported by said receptacle and arranged to guide said spaced leg portions of said movable operating member for movement during actuation of said movable operating member, a valve member fixed to and movable with said movable operating member into and out of position where it closes said discharge opening, stationary sack holding elements fixed to said guiding elements, sack holding elements fixedly mounted on and movable with said movable operating member and with respect to said stationary sack holding elements, said stationary and movable sack holding ele-

ments being in the form of pointed hooks with the points of the stationary sack holding elements being extended in a direction different from the direction of extension of the points of the movable sack holding elements, and means forming part of said valve member which is adapted to abut against a part of said receptacle so as to limit movement of said movable operating member in one direction.
